ASH TRAY

Don O. Benson and Elaine C. Benson, both of R.R. 3,
Box 172A, Prior Lake, Minn. 55372

Filed Sept. 18, 1972, Ser. No. 290,213

Term of patent 7 years

Int. Cl. D27—03
U.S. Cl. D85—2 H

FIG. 1

FIG. 2

FIG. 3

FIG. 4

FIG. 5

FIG. 6

FIG. 1 is a front elevational view of an ash tray showing our new design;

FIG. 2 is a side elevational view thereof;

FIG. 3 is a top plan view thereof;

FIG. 4 is a bottom plan view thereof;

FIG. 5 is a rear elevational view thereof; and

FIG. 6 is a vertical sectional view thereof, taken along line 6—6 of FIG. 1.

We claim:

The ornamental design for an ash tray, as shown and described.
